UNITED STATES PATENT OFFICE

VALENTINE J. MOHLER, OF WHEATON, ILLINOIS, ASSIGNEE, BY MESNE ASSIGNMENTS,
TO THE LIQUID CARBONIC CORPORATION, OF CHICAGO, ILLINOIS, A CORPORATION
OF DELAWARE

BOTTLE-CROWNING MACHINE

Application filed January 8, 1923. Serial No. 611,326.

The bottles and crowns therefor in connection with which my machines are used, are well known in the art. The mouth of the bottle is formed with a small rib or head about the same and the crown or cap which my machine is designed to apply to the bottle is of relatively stiff sheet metal and prior to being fed to the machine is struck up to form a crimped, flaring skirt or flange. The crown is lined with some sealing material such as cork. The machine is designed to feed a crown to each bottle passed therethrough and to force the edge of the crimped skirt or flange inward, under the bead on the mouth of the bottle, whereby the crown is locked upon the bottle.

My improved machine belongs to that class in which a rotary carrier is provided with a concentric series of reciprocating crowning heads located respectively over a series of bottle seats, to which latter the bottles to be crowned are successively fed as the carrier rotates. As in prior machines of this character, after a bottle has been supplied to a seat in the carrier, the crowning head above the seat descends and locks a previously applied crown to the bottle and then recedes, permitting the bottle to be carried out of the machine by suitable means provided for the purpose.

The crowning heads embodied in the particular form of machine chosen to exemplify my invention are of a type disclosed and claimed in my pending application No. 538,537, filed February 23, 1922, and are characterized by an expandable die which during the descent of the head in the sealing or clamping operation is of a diameter to force the crimped flange of a crown on a bottle into locking position and is permitted to expand thereafter to release the bottle.

It is a feature of the present invention that the bottle crowns are fed from a hopper to a holder or presenting device arranged in the path of the bottles in their progress through the machine in which holder the crowns are held in an inclined position in the path of the lips of the bottles so that each bottle as it passes under the holder misses the near edge of the crown presented thereby, but engages

the far edge and pulls the crown out of the holder or presenting means, the crown being thus applied to the bottle in position to be secured thereto by the crowning head as previously explained.

The invention also includes certain improvements in the crown feeding means, in the adaptation of the machine to bottles of different and irregular sizes and other features which will be readily understood from the following detailed description taken in connection with the drawings accompanying and forming a part of the specification.

It is to be understood, however, that the specific disclosure is for the purpose of exemplification only and that the scope of the invention is defined in the following claims in which I have endeavored to distinguish it from the prior art, so far as known to me, without, however, relinquishing or abandoning any portion or feature thereof.

In the drawings accompanying and forming a part of this specification Fig. 1 is a front elevation of a preferred embodiment of my invention; Fig. 2 a side elevation thereof; Fig. 3 a plan partly in horizontal section; Fig. 4 a front elevation of the upper portion of the machine on an enlarged scale and partly in vertical section; Fig. 5 a vertical section through the same on an axial plane at right angles to that of Fig. 4, parts being shown in elevation; Fig. 6 a horizontal section on the plane of line 6—6 of Fig. 4 with a part removed for the sake of clearness; Fig. 7 a vertical section of one of the crowning heads; Figs. 8 and 9, a side elevation and horizontal section, respectively, of a detail; Fig. 10 a vertical section of the same detail on an enlarged scale; Fig. 11 a vertical, axial section through the lower part of the machine, parts being shown in elevation; Fig. 12, a similar section but on a plane at right angles to that of Fig. 11; Fig. 13 a horizontal section on the plane of the line 13—13 of Fig. 11; Fig. 14 a side elevation, partly in section, of the upper part of the machine showing the hopper for feeding crowns to the machine in normal position; Fig. 15 a similar view showing the hopper in lowered position for the purpose of fill-

ing, etc.; Fig. 16 a vertical section of a detail on an enlarged scale; Fig. 17 a front elevation of the machine partly in section on the line 17—17 of Fig. 14; Fig. 18 a plan view of the same showing the hopper in lowered position; Fig. 19 a section on the line 19—19 of Fig. 20 looking in the direction of the arrows and showing the crown chute partly in elevation and partly broken away; Fig. 20 a vertical, central section thereof on the line 20—20 of Fig. 19; Fig. 21 an enlarged fragmentary view on the horizontal plane of the line 21—21 of Fig. 20; Fig. 22 a section on the line 22—22 of Fig. 19; Fig. 23 an enlarged horizontal section on the line 23—23 of Fig. 20 looking upward in the direction of the arrows; Fig. 24 a front elevation showing the crown feeding and presenting devices on an enlarged scale; Fig. 25 a side elevation of the same partly in vertical section; Fig. 26 a vertical section on the plane of the line 26—26 of Fig. 25 looking in the direction of the arrows; Fig. 27 a vertical section on the line 27—27 of Fig. 26 showing in dotted lines a crown passing through the chute in correct position; Fig. 28 a similar view but with the crown improperly faced; Fig. 29 a transverse section on the line 29—29 of Fig. 27 but showing the crown in full lines; Fig. 30 a similar section on the line 30—30 of Fig. 28; Fig. 31 a horizontal section on the line 31—31 of Fig. 25; Fig. 32 a side elevation of a bottle guide for holding a bottle in position in its seat during crowning; Fig. 33 a side elevation of the same part viewed in the opposite direction; Fig. 34 a horizontal section on the line 34—34 of Fig. 32 looking in the direction of the arrows; Fig. 35 a vertical section on the plane of the line 35—35 of Fig. 32 looking in the direction of the arrows; Fig. 36 a bottom plan of the crown presenting device; and Figs. 37 to 40, inclusive, a series of detail views showing the crowning mechanism and a bottle to be crowned in elevation and the crown presenting device in vertical section, the several views representing progressive steps in the operation of applying the crown to the bottle.

50. Each part is identified by the same reference character wherever it occurs in the several views.

In the preferred embodiment of the invention shown in the drawings the machine 55 comprises a base 43 which encloses the driving mechanism and on which the bottle feeding means or carrier *b* is mounted. A standard 44 is also mounted on the base and supports a hopper *c* for receiving and feeding 60 crowns to the machine, the crown presenting device and the crowner assembly *d*. From the hopper the crowns are discharged into a chute 45 by which they are conveyed to the presenting head or device 46 beneath 65 which the bottles are fed successively to re-

ceive the crowns just prior to the descent of the respective crowning heads to secure the crowns to the bottles. The successive bottles are received in seats arranged directly under the respective crowning heads and revolve therewith through a portion of a revolution of the shaft sufficient to permit the crowning operation to be performed thereon.

The crowning head assembly is best shown in Figs. 4, 5 and 6. The heads 42 are slidably mounted in a revolving carrier 47 (see Fig. 5) which is secured to and revolves with the main shaft 48. In the particular exemplification of my invention shown in the drawings there are six crowning heads but obviously this particular number is not essential. The carrier 47 comprises a sleeve 49 splined upon and secured to said shaft, an upper head 50 and a lower head 51, said heads having guiding openings or seats therein arranged in alignment for the purpose of receiving and guiding the crowning heads.

The crowning heads comprise each a barrel 79 and a stem 52, upon the upper end of which is mounted a roller 53 which travels in a stationary cam track 54 as the shaft carrier and crowning head revolve, thereby raising and lowering the head. The cam track is formed in a casting secured by bolts 55 to a casing or housing 56 which encloses said cam, crowning heads, carrier and shaft, and is so designed that as each crowner head reaches the proper position, after a crown has been placed upon a bottle beneath the same, it descends sufficiently to secure the crown on a bottle and then mounts again to release the bottle. A sleeve 57 in the top of the housing forms the upper bearing for the main shaft the lower bearing for which will be described later. A portion 59 of the shell or cylindrical wall of the housing is hinged at 60 to the main body 61 thereof for convenience of access to the interior.

As will later appear the main shaft 48 is splined to the driving mechanism within the base so as to be vertically reciprocable with respect thereto so that it may be raised and lowered with the housing, crowners and associated parts to accommodate bottles of different size. The housing is vertically adjustable upon guide rods 61, which are secured at their upper and lower ends respectively in lugs 44^a, 44^b upon standard 44. The housing is formed with perforated ears 62, 63 which fit and slide upon said guide rods or columns 61 so that the housing may be adjusted vertically with respect to the bottle support. The housing may be conveniently raised and lowered to adjust it by means of a rack 65 secured to the housing and a pinion 66 meshing therewith. Said pinion is journaled on a stub shaft 70 on the standard on which is also journaled a handle 67. The handle and pinion are formed with

mating clutch teeth (see Fig. 6) and the handle may be moved axially upon the shaft into and out of engagement with the pinion so that it may be used to revolve the latter 5 but when not in use may hang vertically upon the shaft.

In order to facilitate the adjustment of the housing and the associated parts to the particular size of bottle to be crowned I 10 provide a gauge 65^a attached to the adjustable housing, substantially in the horizontal plane of the crown holding or presenting device. Conveniently and as shown in the drawings the gauge 65^a is pivoted to 15 a bracket 67^a depending from the housing by means of a screw-bolt 66^a whereby it may be swung to a position above the bottle carrier as shown in full lines in Fig. 9 or to a position outside the line of travel of the bottles as shown in dotted lines in said figure. 20 A spring-pressed ball 68 in the lower face of the bracket engaging depressions 69, 72 in the upper face of the gauge serves yieldingly to hold the gauge in either operative or inoperative position as desired. To adjust the machine the gauge is swung into position over the bottle carrier, a bottle of the size to be crowned is placed beneath the gauge and the housing lowered until the 25 gauge rests on the bottle.

To render the raising and lowering of the vertically adjustable structure easier I have provided a partially counterbalancing mechanism comprising a spring 71 in a casing 35 72, the latter being connected at its lower end to a hook 74 on the frame. A rod 75 extends through the spring and carries at its lower end a washer 73, against which the lower end of the spring bears. Rod 40 75 is connected at its upper end to a cable 76 which extends over a pulley 77 on the standard 74 and is connected to an eye 78 on the adjustable structure.

Any suitable means may be employed for 45 locking the adjustable housing in position on the vertical columns. For this purpose I have shown in Fig. 6 bolts *a'* tapped into the respective lugs 63 of the housing and each having a sleeve *b'* thereon the cam face 50 *c'* of which engages the corresponding column 61 when the bolt is tightened.

As the form of crowning head with its expandable die shown in the drawings is the subject-matter of a separate application, as 55 stated above, it will be described herein only to the extent necessary for an understanding of the invention which forms the subject-matter hereof. I have heretofore described the mounting of these crowner heads in the 60 rotary carrier and the means, including the stems of the crowner heads, for reciprocating them as the carrier rotates. The stem of each crowner head is screwed into the upper end of a cylindrical hollow casting or barrel 79 65 the lower end of which is of enlarged exter-

nal diameter, as at 80, and threaded to receive a nut 81. The nut is formed with an inwardly extending shoulder at 83 which supports an annulus 84 which is clamped between said shoulder and the lower end of the barrel. A horizontal groove approximately semi-circular in cross-section is formed in the nut at 82 and in the annulus at 85 and the lower end of the bore of the nut is flared at 103. The expandable die comprises an annular series of rocking sections 87 each pivoted intermediate its ends by a semi-circular knuckle 86 seated in the groove formed in the nut and annulus as above described, by reason of which construction the die sections are capable of a limited oscillation or swing in their respective radial planes. The inner face of each section is formed with an inwardly projecting portion 88 adjacent its lower end, such portions of the respective sections together forming a continuous ring which constitutes the die proper when the parts are in the position shown in Fig. 7. Above the projections forming the constricted die opening the die sections are somewhat cut away at 87^a and at their upper ends are formed with inwardly projecting bearing faces 89 for a purpose which will appear. The die sections are perforated at 87^b to receive a split ring 87^c upon which the die members are conveniently assembled for insertion into the crowning head.

The lower end of the barrel 79 is chambered at 79^a to receive the upper ends of the pivoted die sections and permit the necessary radial movement thereof and above said chamber has a bore 90. Above the bore 90 the cavity is enlarged as at 79^b forming a shoulder 94. In order to lock the die sections in the die forming position shown in Fig. 7 a locking sleeve 91 is mounted to slide in the contracted passage 90, the lower end thereof being of such diameter that when lowered within the circle formed by the upper ends of the pivoted sections the latter are held against movement. The upper end of the locking sleeve is formed with an outwardly extending flange 91^a which extends over the shoulder 94 and limits the downward movement of the sleeve. A cushioning washer 95 is interposed between said flange and shoulder. The lower end of the sleeve is tapered as at 92 to permit it to readily enter the opening formed by the die sections and force the latter to the contracted position. A plunger 97 is guided at its upper end in the cylindrical bore 98 formed in the lower end of the stem 52 and at its lower end is somewhat reduced in diameter as at 96 where it is guided in the locking sleeve above described. The plunger is formed with an annular flange 99 which, when the plunger is in the lowered position shown, rests upon the upper end of the locking sleeve. A spring 100 is interposed between said flange and the lower end 101 of the stem and normally forces the

plunger and locking sleeve to the lower position shown in Fig. 7. A spring pressed ball 102 releasably holds the sleeve in lowered position.

5 The lower end of the plunger is provided with a head 105 which is concave on its lower face to fit the top of a crown and normally said head projects below and beyond the die of the crowning head.

10 In operation, after a crown has been placed upon the mouth of a bottle occupying the seat below any particular crowning head the latter with the parts in the position shown in Fig. 7 is lowered by the cam mechanism above described. The head 105 first engages the crown and the pressure of the spring 100 on the plunger during the further operation of the device serves to maintain the crown firmly upon the bottle. The further lowering of the crown or head causes 20 the plunger to recede but the locking sleeve is still maintained in operative position by the spring-pressed ball. As the rotary movement continues the crowning head continues 25 its descent so that the crown on the bottle enters the contracted portion of the die by which the flange is pressed inwardly into locking position. The shoulder 107 of head 105 ultimately engages the lower end of the 30 locking sleeve 91 and raises the latter permitting the upper ends of the die sections to move inward and the die opening to be thus expanded. The crown and bottle are thus released and as the rotary movement of 35 the carrier continues the crowning head rises until the die clears the crown. Further upward movement of the crowner head causes the parts to resume the position shown in Fig. 7. While the particular form of crowner head above described is very satisfactory, 40 it is to be understood that the present invention is not limited thereto, as other forms of crowner head may be used in connection with my improved machine.

45 As heretofore stated the crowns are fed from a hopper into which they are dumped holus-bolus, by a chute or run-way to a crown-presenting device from which latter they are removed or stripped by the successive bottles to which they are applied as the bottles pass beneath the presenting device on their way through the machine. The crown presenting device is so located relatively to the actuating cam by which the 55 crowning heads are raised and lowered, that each bottle receives its crown just before the crowning head which applies the crown descends sufficiently to engage the latter on the bottle. As heretofore stated the crowns are 60 fed from the hopper *c* through a chute 45 to the crown presenting device 46 one at a time and in the latter they are presented singly in an inclined position hollow side down in the path of the lips of the bottles and are engaged by the latter on their passage through

70 the machine and stripped from the presenting head. It is obviously essential that the crowns always be presented to the bottles hollow side down in position to be engaged by the bottles. With this in view, the chute is made of dimensions to permit the crowns to slide edgewise therethrough and to prevent the crowns turning over therein, and the hopper is provided with mechanism designed to permit crowns to enter the chute 75 only when faced in the proper direction notwithstanding that the mass of crowns in the hopper is promiscuously mixed. The hopper and the mechanism by which crowns suitably faced only are fed to the chute may 80 best be understood by reference to Figs. 1, 2 and 14 to 22 inclusive. As seen in Figs. 1 and 2 the front wall of the hopper is substantially vertical and the bottom wall slopes downward toward the front wall so that during the operation of the machine the crowns in the hopper constantly gravitate toward the front wall where the sorting mechanism to which reference has been made is arranged.

85 The mouth or entrance to the chute is arranged at the angle or corner between the front wall and the inclined bottom so as to receive such of the crowns as are permitted to pass into it by the sorting mechanism, see 90 Figs. 14 and 20. The single moving element of the sorting mechanism is a rotary disk 111, which fits over and substantially closes a circular opening in the front wall of the hopper and is mounted on a revolving, 95 horizontal shaft 112. As best seen in Fig. 14 said shaft is mounted in a bushed bearing 113 in the main casting of the hopper and projects at its rear end through the rear wall of the hopper where it is provided with a clutch element 149 by which it is driven as will be presently described. The front end of the shaft 112 is reduced in diameter, see Fig. 20, and extends substantially beyond the front wall of the hopper and the sorting disk 111 is formed with a hub 115 fitting upon the reduced portion of said shaft and is releasably locked thereto by a spring pressed pin 116. By withdrawing the pin against the resistance of its spring the disk may be drawn away from the circular aperture in the front wall of the hopper to obtain access to this portion of the hopper in case the machine becomes clogged, or if crowns are to be discharged.

100 110 The lower wall or floor of the hopper terminates short of the front wall thereof by a little more than the thickness of a crown, as at 113^a, Fig. 20. The approximately circular opening in the front wall of the hopper merges at this point into the flaring mouth of the crown chute or guide section 120, the edge walls and back of which are formed integrally with the main casing of the hopper. An annular face plate 124 is secured 115 120 125 130

to the front wall of the hopper around the sorting disk, and extends downwardly at 124^a to form the front wall of the mouth or entrance of the chute. Wings or webs 122, 5 see Figs. 19, 20, cast integrally with the hopper overlap the circular opening in the hopper so that an approximately U-shaped narrow vertical space 117 is formed about the circular opening which space is of just sufficient width to receive a crown edgewise. 10 Preferably the mouth or entrance of the chute is partially occupied by a guide block 136, see Fig. 19 which prevents choking at this point.

15 The inner face of the disk is provided with a series of buttons 125 which, as the disk revolves, move through the narrow U-shaped chamber just described and permit such of the crowns as are presented flatwise against the 20 disk with their hollow or bottom side forward to enter the chute but arrest those which are reversely faced. As before observed, the crowns prior to their application to the bottles are frustro-conical or flaring. The heads 25 of the buttons are of such diameter and so spaced that the distance between the nearest points of adjacent button heads is less than the greatest or bottom diameter of the crowns but more than the least or top diameter thereof. The distance between the 30 shanks of adjacent buttons however is slightly greater than the greatest diameter of the crowns. Consequently, if a crown is fed flatwise against the disk with the hollow side 35 forward it will pass between adjacent buttons and enter the chute. On the other hand if a crown is presented to the disk convex side forward it is arrested by the buttons because its flaring skirt cannot pass between the button heads. The crowns are kept in motion by 40 radial vanes or wings 135 which stir the crowns as the disk is revolved so that a crown rejected because of its position when it encounters the disk is carried away and sooner 45 or later presented in proper direction to enter the chute. It sometimes happens that a crown which encounters the disk in reversed position is carried up between adjacent buttons, see dotted lines Fig. 19 and it is necessary 50 or desirable for the continued operation of the device that it be dislodged. For this purpose the hopper is provided with a stripper 128 the form of which is shown in Figs. 19 to 22 inclusive. The stripper comprises 55 an arcuate flange 130 secured by screws 129 to the annular face plate 124 and a concentric channel which is of suitable cross-section to permit the buttons to travel therethrough. The stripper is made with an outer tapered prong 132 and an inner tapered prong 133, the advance or forward edge 134 of the stripper being inclined between these 60 prongs as shown in Fig. 19. The forward side of the stripper is formed with ribs 134^a concentric with the sorting disk, and concen-

tric channels 134^b are formed in the latter to receive said ribs. In the particular arrangement shown and described the disk revolves in the direction of the arrow *a* shown in Fig. 19 and any crowns which may be caught or held between the ends are dislodged by the 70 stripper which enters between such crowns and the disk.

From the foregoing it will be evident that as the mass of crowns within the hopper gravitates toward the sorting disk each crown 75 therein will ultimately reach a position in which it is kept in motion and turned over until it lies flat against the rim of the disk. If it then happens to have its hollow side 80 forward or toward the disk it slips between the buttons; otherwise it is rejected by the disk and carried up and subject to the further stirring action of the disk until ultimately it arrives at the mouth of the chute 85 in proper position to escape between the adjacent buttons.

In order to prevent undue pressure on the crowns in contact with the disk in the event that the hopper is filled or substantially so, 90 I provide a baffle 138 extending from the front wall of the hopper which sustains a portion of the weight of the crowns in the front part of the hopper, but is so inclined as to permit them to gravitate towards the 95 bottom of the hopper as required.

It is desirable because of the height of the machine to so mount the hopper thereon that it may be lowered for the purpose of filling or to give access thereto from above. For 100 this purpose, the hopper and the flaring throat or entrance to the crown chute are separable from the main portion 139 of the chute and the hopper is mounted on swinging arms to permit it to be lowered to a position in front of the machine, the driving connection for the disk being separable for this purpose. This construction is best shown in Figs. 14 to 18 inclusive. The bottom of the hopper is formed with inclined 105 ribs 140 which rest upon seats 141 formed on the casting 142 secured to the housing of the crowner head mechanism, the seats and ribs being inclined as shown particularly in Fig. 15. Parallel motion arms 143, 144 are 110 pivoted to the main hopper casting and to pivot studs 144^a secured in bosses 145 suitably located for this purpose on the housing, 115 see Figs. 15, 16 and 25. Spring housings 145^a are also mounted on said pins 144^a and coil springs 146 in said housings are secured at one end to the respective pins and at the other to pins 147 projecting from the respective parallel motion arms 143, 144, it being the purpose of the springs to resist the downward movement of the arms and hopper and therefore facilitate the lowering and raising 120 of the latter.

The rear end of the disk shaft 112 is formed with a toothed clutch face 149 as previously 125

stated, and shaft 150 is horizontally journalled on the housing and provided with a similar clutch face 149^a which normally meshes therewith. Shaft 150 is mounted in bearings 151—152 in casting 142 to which reference has already been made and provided with a bevel pinion 153 which meshes with a bevel gear 154 on the top of the main shaft so that when the hopper is in normal position the disk is driven from the main shaft by the mechanism just described. The hopper may be locked in normal position by latches 156 pivoted upon the hopper and engaging pins 157 upon the housing.

As heretofore stated the upper section 120 of the chute by which the crowns are carried from the hopper to the crown presenting device is carried by the hopper and is therefore necessarily separable from the stationary section 139 of the chute. Normally, however, it is immediately above and in registry therewith. In order to prevent any crowns contained in this upper section of the chute falling out when the hopper is lowered I provide an automatic gate 159 for closing the end thereof. The gate comprises a bail 160 which is pivoted to said chute section and a tongue 161. A spring 163 at each side of the gate tends to assist gravity in swinging the gate into a position to shut off the end of the chute. Normally, however, as seen in Fig. 20, the gate is held up in inoperative position by contact with the upper end of the stationary section of the chute. The stationary section 35 of the chute is secured to the housing of the crowner mechanism heretofore described, and comprises the channelled member 550 and face strips 553, which latter retain the crowns in the channel, see Figs. 20 and 27 to 30.

As the crown presenting device must have a slight vertical movement, as will be herein-after more fully explained, the lowermost section of the chute is constructed to rise and fall with the crown presenting device and to have a sliding engagement with the fixed section. Provision is also made at the junction of the fixed and sliding sections for the elimination from the chute of any crowns which may enter the chute in the reversed position notwithstanding the mechanism for preventing this which I have previously described in connection with the hopper.

Referring to Figs. 25 to 30, inclusive, it will be observed that the channel 554 of the stationary member is slightly broadened at the lower end as at 555 and the upper end 556 of the sliding or vertically movable section is provided with a pair of extension guides 557 which slide within the widened portion of the channel in the stationary member, the inner or adjacent edges of the extensions being spaced apart a distance substantially equal to the width of the main portion of the channel so as to form an extension of the latter and permit the passage of crowns.

The upper end of the lower vertically movable chute member is also formed or provided with a tongue 558 which extends between and in the plane of the face strips 553 (see Figs. 23 and 24). Provision is thus made for the vertical movement of the crown presenting device and the attached chute section without interfering with the feeding of the crowns. It may sometimes happen that notwithstanding the provision to the contrary an occasional crown will enter the chute in the reversed position, that is to say with the hollow side of the crown to the rear as seen in dotted lines in Fig. 28 and in full lines in Fig. 30. I provide for the discharge of any such improperly faced crowns as follows: The lower end of the stationary channel member is cutaway at 560, see Figs. 26 to 28, and the upper end of the vertically movable member of the chute is cut away at 561 so that an opening is left in the rear wall of the chute at this point suitable for the discharge therethrough of a crown. The guide members 557 are formed on their respective adjacent surfaces with ribs 557^a intermediate the front and rear edges thereof. When a properly faced crown reaches these extensions in its travel from the hopper towards the presenting device the edge of its skirt enters the space between said rib and the face strips 553 and is guided past the rear opening in the chute, see Figs. 27, 29. When a reversed crown arrives at the extensions, however, the edge of its skirt enters the recess between said ribs and the rear wall of the channel and as it comes opposite the opening it is directed outwardly therethrough by the shape of the ribs as will be apparent from an inspection of Figs. 28 and 30. A trough 562 at the rear of the chute carries away any crowns discharged in this manner.

Referring now more particularly to Figs. 2, 4, 5, 24, 25, and 31, it will be noted that the movable section of the chute curves inward and terminates in the crown presenting device 563 which is located immediately below the path of the crowner heads and somewhat in advance of the downward dip of the cam for lowering the crowning heads. The lower end of the movable member of the chute is guided by a bracket 564 depending from and secured to the adjustable housing. The bracket comprises a pair of cheek pieces 566 and a cross bar 567 formed integral therewith. The cheek pieces are formed with inwardly extending vertical guide flanges 568 and vertical slots 569. Rollers 570 secured to opposite sides of the chute are guided between the flanges and other rollers 571 likewise mounted on the chute extend into the slots in the respective cheek pieces. Thus the movable chute is guided at its lower end and permitted a vertical movement. The downward movement of the chute, however, is limited by adjustable stop bolts 572 which

engage lugs 573 on the respective opposite sides of the chute when the latter is in its lowermost position. Preferably a compression spring 574 is interposed between a bracket 575 on the housing and a shoulder 576 on the chute whereby the chute is yieldingly maintained in its lowermost position.

As shown in Figs. 5, 25 and 36 the crown presenting head is formed with a downwardly opening channel composed of side flanges 577 and a top wall 578, the latter being inclined downwardly from the entering end of the channel to the rear end thereof. Before the machine is put in operation the movable chute member and crown presenting head are so adjusted that notwithstanding irregularities in height all bottles of the same approximate size will enter the channel, and engage the inclined top wall as they are carried around and more or less raise the chute according to the somewhat irregular heights of the successive bottles. This is important, as will appear more particularly from an inspection of Figs. 37 to 40 inclusive, in order that the top edge of every bottle may be presented to the crown in the crown presenting device in exactly the same relative vertical position.

As best seen in Fig. 36, the crown passage 554^a of the movable lower chute section as it enters the crown presenting device is diverted substantially into the direction of the bottle head guiding channel in the latter and is so inclined that it intersects the top wall 578 of the channel for the bottle heads in the bottom of the crown presenting device at an acute angle to the horizontal (see Figs. 36 and 37). A stop pin 579 is yieldingly maintained by spring 580 with its inner end extending into the path of the crowns through the edge wall of the crown conveying channel so as to arrest the lowermost crown in the chute in the position shown in Figs. 36 and 37. In this position, the rearward edge of the skirt of the crown projects slightly below the top wall of the bottle head guide so that, as a bottle advances through the guide, the lip thereof misses the near edge but engages the far edge of the skirt and carries the crown with it releasing it from the pin 579 and from the chute. At the same time it is to be understood that the crowning head which is being carried along in registry with the bottle passes over the crown presenting device and is lowered by the cam construction above described so that the plunger head thereof makes contact with the upper surface of the crown presenting head and is guided in its forward movement and descent in the channel 581 formed therein so as to secure accurate registry with the crown and with the bottle. The pitch of the cam controlling the vertical movement of the crowning heads is sufficiently steep at this point so that the plunger of the crowning head makes contact

with the bottom of the channel and is slightly repressed thereby. When it reaches the position shown in Fig. 39, the plunger drops off the edge of the crown presenting head and bears upon the crown, pressing it firmly onto the lip of the bottle. The further movement of the crowning head plunger and bottle with the cap clamped between them results in the withdrawal of the cap or crown, as shown in Fig. 40. The next crown then descends to the position to be engaged by the following bottle. The crown chute is kept supplied with crowns by the hopper mechanism above described so that a crown is always in position to be engaged and withdrawn as the successive bottles reach the presenting device.

I have heretofore referred to the fact that during the period that the bottles are being crowned they are revolved about the axis of the machine through a limited arc while in axial alignment with the respective crowners by which the crowns placed on the bottles are secured thereto. For this purpose, a circular rotary table 326 revolves with the main shaft and is provided with an elastic annular pad 327 upon which the bottles rest during the crowning operation. Said table is mounted on a sleeve 304 which is keyed to the main shaft. Immediately above the rotary table, is a star wheel comprising a second sleeve 328 fitting the first mentioned sleeve and formed or provided with radial arms 329, between which are the recesses 324 of generally semi-circular form to receive the bottles to be crowned, see Figs. 3 and 11. For convenience of assembly the star wheel is formed in halves (see Fig. 3) which are firmly united when assembled by reason of the tapered ends of sleeve 328 (see Fig. 11) engaging corresponding seats in the rotary table 326 and nut 330, screwed upon the threaded end of sleeve 304.

As the bottle support and star wheel revolve each recess or seat in the latter receives a bottle before it reaches the crown presenting device above described which bottle is firmly held during the crowning operation. The bottles are fed to the support automatically through a guide channel and over a table *a* the upper surface of which is in the plane of the support. A friction feed disc 331, the upper surface of which is in the same plane as the top of the table and the upper surface of the support 326, carries and forces the bottles to the latter. The disc is positively rotated from the main shaft through driving means so designed that in case of a jam the driving mechanism may slip without damaging the machine. The disc 331 carries gear 334 which meshes with and is driven by a gear 325 on the sleeve 304 to which reference has already been made. Gear 334, however, is not locked to disc 331, but is journaled on the hub 332 thereof so as to be ca-

pable of rotation relative thereto. Normally, however, the disc and gear wheel revolve together due to a frictional engagement which I will now describe. The hub of the disc is provided with a flange 336 between which and the upper face of the gear 334 is interposed a washer 335 of friction material. An annulus 337 is mounted on the gear 334 to revolve therewith and held in frictional contact with flange 336 on the hub of the disc by means of bolts 338 and springs 339. The construction just described provides sufficient frictional engagement to turn the disc under normal condition, but in the event of a jam 15 and the disc becoming locked, the gear wheel slips on the hub of the disc thus avoiding breakage.

The bottles fed to the machine are guided over the table and feed disc and to the rotary 20 support by stationary guides 340, 341, 342, 343 and 344 and normally stationary guides 345 and 362, see Fig. 3.

Beyond guide 362 is a stationary guide 361, the guiding surface of which is substantially 25 concentric with the main shaft and at a distance therefrom and from the star wheel to properly permit the bottles seated in the latter to pass but to hold them in their seats. Guides 345 and 362 bridge a gap between stationary guides 344 and 361. They are so pivoted and spring-pressed however as to yield from the normal position shown in Fig. 3 to prevent jamming or breaking a bottle. Guides 340, 341, 342 and 361 are bolted to the 30 table and guide 343 to a segment 346, the latter being bolted to the table and projecting over the friction disc 331. Guide 344 is formed with webs 350 and 351 and collars 352 and 353 by which said guide is secured to post 354 mounted on boss 333 on which the feed disc is journaled. As best seen in Fig. 3, the first of the yielding guides, 345 is pivoted to the short arm 355 of bell crank 355 also mounted on post 354. A bolt 357 is pivoted 35 to 358 to guide 345 and extends through an eye 359 on the long arm of the bell crank. Between shoulder 360 of said bolt and the eye 359 is compressed a spring 356 for normally pressing guide 345 toward normal position. Guide 362 is pivoted to the free end of guide 345 at 363 and normally occupies the position 40 shown in Fig. 3. It is formed with a tail piece 364 slotted at 365 to receive a pin 366 on stationary guide 361. The tail piece is 45 formed with an offset 369 and guide 345 with a similar offset 368 and a tension spring 367 connects the offsets. Obviously the construction just described is such that the guides 345, 362 are normally maintained in position 50 shown in Fig. 3 but are repressed to prevent breakage in case for any reason a bottle does not properly enter its seat in the star wheel.

The bottles to be crowned are fed into the mouth of the channel at 398 between guides 55 340 and 343 and onto the friction feed disc.

The friction of the bottles on the feed disc is sufficient to carry them successively into position to be received by the star wheel and to force them into the seats thereon as the latter are presented. The yielding guides complete the adjustment of the bottles to the 70 seats.

It is of particular importance that the bottles be firmly held in the seats of the star wheel during the crowning operation. I 75 have therefore provided yielding spring-pressed guides at this portion of their path as best seen in Figs. 3 and 32 to 35 inclusive. This guiding mechanism includes a frame casting 375 comprising a vertical wall 379 and a horizontal flange 380, the latter being provided with slotted openings 376 for bolting it in adjusted position on the table. The curved inner face of the wall 379 is arranged substantially concentric with shaft 48 but at such distance therefrom and from the seats in the star wheel that the bottles carried by the latter may freely pass. The vertical, curved wall of the guide is cut away at 379^a to form an opening, the configuration of which is well shown in Fig. 33, through which project certain spring pressed bottle guides of a construction and for a purpose which will now appear. The left hand guide, as the construction appears in Figs. 32 and 34, comprises a barrel 388^a and a pair of curved guide bars 386, 387 integral therewith. Barrel 388^a is pivoted on a post 383 extending between upper and lower lugs 381 on the left hand end of the guide frame as seen in Figs. 32 and 34. The other pivoted guide comprises barrel 388 and curved, horizontal guide bars 389, 390, integral therewith, the barrel being pivoted on a post 384 extending between upper and lower lugs 382 at the right hand end of the guide frame. By an inspection of Figs. 33 and 35 it will be noted that the curved guide arms on one of the pivoted guides alternate 90 with the curved guide arms on the other of the pivoted guides and that all of them are arranged within the opening through the guide frame, and normally project at their free ends slightly beyond the inner surface of the curved wall 379. They are normally 95 and yieldingly maintained in this position by tension springs 393 connecting arms 391 and 392 on the respective pivoted guide members. The free ends of the horizontal, curved guide arms are chamfered as at 395 so as to yield to a bottle forced longitudinally of the guiding device and the inner or pivoted ends of the guide bars are substantially in the same cylindrical surface 100 as the inner face of the curved guide wall 379. An examination of Fig. 34 and the dotted lines thereof will make it plain that throughout the length of the opening in the guide member, which corresponds to the 105 travel of the bottles during the time they 110

are being crowned the latter are subjected to yielding pressure which holds them firmly against the seats in the star wheel and therefore substantially co-axial with the vertically moving crowning heads.

5 Beyond the yielding guide device just described the table is provided with adjustable stationary guides 396^a, 396^b and 396^c on one side of the bottle path and 397^a and 397^b on 10 the other side of the bottle path. As seen in Figs. 3 and 4 guide 397^a is bifurcated at its forward end to provide fingers 397^c which extend between the vertically spaced bars of the star wheel and serve to strip the bottles from the latter.

15 It will be understood that bottles are continuously supplied, automatically or otherwise to the entrance 398 of the bottle channel. As they successively reach the feed disk 331 they are carried around between the opposite guiding surfaces and pushed onto the stationary table and forced by the following bottles into the successive seats in the star wheel and onto the revolving table as the 20 successive seats are presented. The yielding guides 345 and 362 cooperate in properly placing each bottle in a seat in the star wheel as will be readily understood. The continued revolution of the star wheel carries the bottles past the guide 361 and past 25 the spring guide device and while in contact with the latter each bottle is crowned by the crowning mechanism previously described. Before the bottle reaches the guide 30 397^a the crowning head by which it has been crowned has risen to free the bottle and it is stripped by said guide and forced by the following bottles through the guide channel and out of the machine.

29 In the specific embodiment of the invention chosen for exemplification the table 302 forms a part of the main casting or frame 301, and the latter is bolted to a suitable base 300 as best seen in Figs. 11, 12 and 13. Sleeve 304 to which reference has been made, is journaled in a bearing 303 formed integrally with the main frame or casting and receives the main shaft 48 which is splined thereto and revolves therewith, but may be adjusted 35 therethrough for the purpose of adjusting the crowning mechanism as heretofore described. The bearing is bushed at 305 to fit the sleeve and at its upper end is expanded to form an annular chamber and shoulder 40 which receives the ball bearing 306. The ball bearing receives the weight of sleeve 304 which for this purpose is formed with a flange or collar 307 which rests upon the ball bearing. The gear-wheel 325 by which gear 334 is driven from the main shaft, as previously described, rests upon the flange 307 and in turn supports the rotary bottle support or table 326 heretofore described.

45 At its lower end sleeve 304 is reduced in diameter, as at 308, to receive a collar 309

carrying a worm gear 310. The collar is held in place by a nut 311 threaded on the lower end of the sleeve. A horizontal worm shaft 312 is journaled in the main casting at 313 and 314, and engages the worm gear for rotating the gear, sleeve and shaft. At its right-hand end, as seen in Fig. 11 the worm shaft is provided with a spur gear 315 which meshes with a similar gear 316 on a countershaft 317. The latter may be locked to co-axial shaft 318 by a clutch 319 of any suitable character.

70 The clutch shifter is shown at g. Shaft 318 carries at one end a large spur gear 320 which is driven from motor 322 by pinion 321.

75 From the foregoing it will be understood that in operation the main shaft is continuously driven from the motor through the connections described above. The bottle support and crowning assembly are directly carried and revolved by the main shaft and the friction feed disk indirectly through the gearing described. The parts being in the position shown in Figs. 1 and 2 and the hopper containing a charge of crowns, bottles 80 are fed automatically or by hand and as rapidly as they are taken up into the entering end of the bottle channel at 398, see Fig. 3. As each bottle is shoved onto the friction feed disk it is carried around between the guides, 85 and when it reaches the position at which the guiding channel leaves the disk is pushed on to the table by following bottles. As the star wheel and bottle support are continuously revolved bottle seats in the latter are 90 continuously presented to the bottles fed by the feed disk over the table and the foremost bottle is fed into the first seat presented, the spring pressed knuckle guide yielding as 95 much as is necessary for this purpose. As the 100 bottles are carried successively under the crown presenting device, being firmly held by the star wheel and acting resilient guides, they first engage the inclined underface of the crown presenting device raising it more 105 or less according to the height of the particular bottle in question, see Fig. 37, and sliding under the edge of the crown presenting device engage the remote edge of the lowermost crown therein, see Fig. 39. The cam 110 controlling the vertical movement of the crowning heads is so designed that as each crowning head travels along in alignment with the bottle to be crowned thereby it descends and the plunger head thereof, which 115 is slightly repressed by gradual engagement with the upper surface of the crown presenting device drops off the far edge thereof, as seen in Fig. 39 onto the rear upper surface of the crown which has been engaged by the bottle. The crown is thereby gently held 120 against the lip, the further movement of the latter extricating the crown from the presenting device whereupon it drops into position 125 on the lip of the bottle and is yieldingly

held thereon by the plunger as seen in Fig. 40. As the bottle, crown and crowning head continue their progress in unison, the crowning head is forced by the stationary cam 5 downward until the crown is pressed into the die, forcing the flange or skirt of the crown into locking position as described at an earlier portion of the specification. It will be understood of course that the channel leading 10 to the crowning head is kept constantly filled with crowns faced in the proper direction as heretofore described by the hopper and cooperating parts so that there is always a crown in the presenting device ready for 15 each bottle. After the crown has been locked to the bottle the further descent of the crown head opens the die and the crowning head is then elevated by the stationary cam this freeing the bottle which is then guided out of 20 the machine as previously described.

I claim:

1. In a bottle crowning machine, a rotary carrier, a series of crowning heads reciprocable on said carrier, a normally stationary 25 cam for reciprocating said crowning heads as they are revolved, a housing to which said cam is secured, a standard, a pair of guide rods on said standard, eyes on the housing sliding on said guide rod and means for vertically adjusting and locking the housing on 30 said guide rods.

2. In a bottle crowning machine, a rotary bottle support, a rotary carrier, a series of crowning heads reciprocable vertically in 35 said carrier, a stationary cam for reciprocating said crowning heads as they are revolved, a cam support vertically adjustable for bottles of different sizes and a gauge arm on said cam support removable into and out 40 of the path of the bottles and adapted to cooperate with a bottle to gauge the vertical adjustment of the cam support.

3. In a bottle crowning machine, a rotary bottle support, a rotary carrier, a series of 45 crowning heads reciprocable on said carrier, a normally stationary cam for reciprocating said crowning heads as they are revolved, a support for said cam, means for adjusting the support vertically to accommodate bottles 50 of different sizes and a gauge arm pivoted on the adjustable support to move in a horizontal plane into and out of the line of travel of the bottle and to cooperate with a bottle on its support to determine the proper adjustment of the cam support.

4. In a bottle crowning machine, a rotary bottle support, a rotary carrier, a series of crowning heads reciprocable on said carrier, a normally stationary cam for reciprocating 60 said crowning heads as they are revolved, a support for the cam, means for adjusting the support vertically to accommodate bottles of different sizes, a gauge arm pivoted on the cam support to move horizontally into 65 and out of the path of the bottles and yield-

ing means to hold the gauge arm in position.

5. A bottle crowning machine comprising a rotary bottle support, a rotary carrier, a series of crowning heads reciprocable on said carrier, means for reciprocating said crowning heads as the carrier rotates; a crown presenting device adapted to present crowns to the bottles as they are carried past it on the bottle support, a chute for carrying crowns to such crown presenting device, a 70 hopper for feeding crowns to said chute, said hopper normally mounted on top of the machine and means connected to the hopper and the main frame of the machine for supporting the hopper in a lowered position. 75

6. In a bottle crowning machine, a vertical main shaft, a rotary bottle support and a rotary carrier carried thereby, a series of crowning heads reciprocable on said carrier, means for reciprocating the crowning heads 80 as the carrier is revolved, a gear on the upper end of the vertical main shaft, a hopper removably supported on the machine, a rotary crown feeding device on the hopper, severable means for rotating said crown feeding device from said gear wheel and means connected to the hopper for supporting it in lowered position. 90

7. In a bottle crowning machine, a vertical main shaft, a rotary bottle support and a rotary carrier carried thereby, a series of crowning heads reciprocable on said carrier, means for reciprocating the crowning heads as the carrier is revolved, a crown presenting device arranged to apply crowns to the 95 bottles as they are revolved, a chute for supplying said device with crowns, a hopper normally resting on the machine and communicating with said chute, a rotary crown feeding device in the hopper, severable connections between said crown feeding device and main shaft for operating the former, and means for carrying said hopper from normal position to a lowered position and supporting it in the latter. 100

8. In a bottle crowning machine, a vertical shaft, a bottle support and carrier mounted thereon and rotatable therewith, reciprocating crowning heads in the carrier, means for reciprocating the crowning heads as the carrier is revolved, a hopper, a divided chute the upper member of which is connected to said hopper, a crown presenting device to which the lower member of the chute is connected, a revolute crown feeding device in 115 the hopper, a horizontal shaft on which said device is mounted, a gear wheel on the vertical shaft, a pinion in mesh with said gear wheel, a horizontal shaft on which said pinion is mounted and a severable clutch connecting the last mentioned shaft with the shaft of the crown feeding device. 120

9. In a bottle crowning machine, a vertical main shaft, a bottle support and a carrier mounted thereon and revolving therewith, 125

vertically reciprocable crowning heads mounted in the carrier, means for reciprocating said crowning heads as the carrier revolves, a hopper, seats on said machine on which the hopper is removably seated, parallel motion arms pivoted to said hopper and to the main frame of the machine whereby the hopper may be lowered from its seat on the main frame, a rotary crown feeding device in the hopper and severable connections for driving said device from the main shaft.

10. In a bottle crowning machine a vertical main shaft, a bottle support and a carrier carried by said shaft, vertical reciprocable crowning heads on the carrier, means for reciprocating said crowning heads as the carrier revolves, a hopper, a seat on the main frame for said hopper, parallel motion arms connected to the main frame and to the hopper whereby the hopper may be lowered from said seat to a filling position, a divided shaft the upper member of which is connected to said hopper, a crown presenting device in the path of the bottles on the support connected to the lower member of said chute, a rotary crown feeding device in the hopper, a horizontal shaft on which said device is mounted having a clutch face at its rear end, a gear on the upper end of the vertical shaft, a pinion meshing with said gear, a horizontal shaft section on which pinion is mounted and a clutch face on said shaft engaging the clutch on the shaft of the crown feeding device.

35. 11. In a machine of the class described a movable bottle support, a bottle crowner in vertical alignment and movable therewith, a crown presenting head having a channel in the bottom thereof in the line of movement 40 of the bottle support to receive the mouth of a bottle to be crowned, said device having a channel intersecting the above-described channel at an acute angle to the horizontal and adapted to convey crowns into a position to be engaged by bottles passing beneath said head, and means for yieldingly holding the crowns in position to be engaged by the bottle heads.

50. 12. In a machine of the class described a bottle support and a vertically reciprocable crowning head, means for moving said support and crowning head laterally in unison, a crown-presenting device for holding a crown at an acute angle to the horizontal in the 55 path of a bottle head on said support so that the mouth of the bottle will engage the far edge of the skirt of the crown, guides in which said device is vertically reciprocable and means for maintaining the crowning head in elevated position to pass the crown-presenting device and lowering it to engage the crown on a bottle after passing the crown-presenting device.

55. 13. In a machine of the class described, a 60 crowning head comprising a plunger and a

die through which said plunger is movable, a bottle support beneath said head, means for moving the head and support laterally together, means for presenting a crown at an acute angle to the horizontal in the path of a bottle on said support so that the bottle in its lateral movement moves beneath the crown and engages the far edge thereof, and means for lowering the head so that the plunger engages the crown while still held by the presenting device and then the die descends to seal the crown on the bottle.

14. In a machine of the class described, a crowning head comprising a plunger and a die through which said plunger is vertically 65 movable, a bottle support beneath said head, means for moving the head and support laterally together, an upwardly yielding crown presenting device having a lower surface inclined upwardly in the direction from which a bottle on the support approaches said device, and a crown seat, the latter being at an acute angle to the horizontal whereby a bottle may slightly lift the device and engage the crown held thereby, and means for lowering 70 the head and plunger whereby the plunger first engages the crown clamping it on the bottle and then the die descends to seal the crown on the bottle.

15. In a machine of the class described, a 75 crowning head comprising a die for crimping a crown on a bottle, a bottle support beneath said head, means for moving the head and support laterally together, a crown presenting device having an under surface upwardly 80 inclined in the direction from which the bottle on the support approaches the presenting device, and for holding a crown at an acute angle to the horizontal in the path of said bottle so that the bottle in its lateral movement moves beneath the crown and engages the far edge thereof, a chute for supplying the presenting device with crowns comprising an upper fixed section and a lower section 85 telescoping therewith, the crown presenting 90 device being carried by the chute so that it may yield upwardly when a bottle slides along the inclined lower surface thereof, and means for lowering the head so that the die engages and crimps a crown on the bottle when the 95 head and bottle have passed the crown presenting device.

16. In a machine of the class described, a bottle support and a crowning head movable horizontally in unison, said crowning head 100 also being reciprocable vertically, and comprising a die and a spring pressed plunger movable through the die, a crown-presenting device arranged in the path of bottles on said support, means on said crown-presenting device to yieldingly hold a crown thereon at an acute angle to the horizontal in the path of a lip of a bottle on a support, and a cam adapted to lower the crowning head as it passes above the crown-presenting device 105

whereby the plunger engages the crown and presses the same on the bottle before the crown is released from the presenting device.

17. In a machine of the class described, and in combination with the stationary frame thereof, a bottle support and a vertically reciprocating crowning head, means for moving said support and crowning head laterally in unison, a crown-presenting device, a guide on the frame in which said crown-presenting device is vertically movable, means for limiting the downward movement of the device, yielding means resisting the upward movement of the device, the under face of the device being inclined downwardly in the path and direction of movement of the lips of the bottles thereunder, whereby the lips of the bottles being crowned will engage the inclined under face of said crown presenting device and move the same upward.

18. In a machine of the class described, a bottle support adapted to move a bottle laterally in a substantially horizontal plane, a vertically reciprocating crowning head movable laterally with the bottle support and comprising a die and spring pressed plunger movable therethrough, a crown-presenting head for holding a crown at an angle to the horizontal and with the top and bottom of said crown partially exposed in the path of a bottle on said support so that the bottle lip will pass under the near edge of the crown and engage the far edge thereof and means for lowering the crowning head as it is carried over the crown-presenting device to cause the plunger to engage a crown in said device at approximately the same time as it is engaged by the bottle thereunder.

19. In a machine of the class described, a bottle support and a crowning head movable laterally in unison, said crowning head also being reciprocable vertically, a spring pressed plunger in said head, a die surrounding said plunger, a crown presenting device arranged in the path of bottles on said support, means on said crown presenting device to yieldingly hold a crown to be engaged by a bottle at an acute angle to the horizontal in the path of a bottle head so that the crown will be withdrawn from said device by the engagement of the head of a bottle with the far edge of the skirt of the crown, means for lowering the crowning head as it travels over the crown presenting device to permit the plunger to yieldingly engage the upper face of the crown presenting device and on further movement of the crowning head to engage the crown on the bottle.

VALENTINE J. MOHLER.
